The ornamental design for a dual-port VOIP analog telephone device, as shown and described.

DESCRIPTION

FIG. 1 is a top, rear perspective view of the present invention, showing the dual-port analog telephone device of the new design;

FIG. 2 is a top, front perspective view thereof;

FIG. 3 is a left side elevational view thereof;

FIG. 4 is a right side elevational view thereof;

FIG. 5 is a front elevational view thereof;

FIG. 6 is a rear elevational view thereof;

FIG. 7 is a top plan view thereof; and,

FIG. 8 is a bottom plan view thereof.
